UNITED STATES PATENT OFFICE

110,902

DESIGN FOR A COMBINED BOWL AND BASE THEREFOR

Edna J. Loesch, Bloomfield, N. J.

Application May 23, 1938, Serial No. 77,345

Term of patent 7 years

To all whom it may concern:

Be it known that I, Edna J. Loesch, a citizen of the United States, residing at Bloomfield, county of Essex, and State of New Jersey, have invented a new, original, and ornamental Design for a Combined Bowl and Base Therefor, of which the following is a specification, reference being had to the accompanying drawing, forming part thereof.

Fig. 1 is a perspective view of the combined bowl and base therefor, showing my design.

Fig. 2 is a perspective view illustrating the bowl and base in separated relation, a portion of the base being broken away in order to show a cross-section.

Fig. 3 is a bottom plan view of a portion of the base.

The distinctive features of the design are the deep bowl having the inwardly directed bead about the rim of the bowl and the truncated tapered bottom and the base in the form of a heavy ring having a tapered inner circumference and a curved flaring downwardly inclined top portion and an annularly corrugated bottom, all as shown.

I claim:

The ornamental design for a combined bowl and base therefor, substantially as shown and described.

EDNA J. LOESCH.
